UNITED STATES PATENT OFFICE.

RUSSELL Q. SCOTT, OF DAYTON, KENTUCKY.

CHECKING DEVICE.

Application filed April 11, 1927. Serial No. 182,595.

This invention relates to checking devices and particularly to a character of device which may be used in segregating and supporting groups of laundry.

It is therefore an object of this invention to provide key racks and tag sets for use in a system in which each rack has special characteristics which render it capable for receiving only a certain lot of similarly tagged laundry pieces permitting indiscriminate commingling of the tagged pieces of each lot in washing operations and positive assorting subsequently by the act of racking the tagged pieces, thereby preventing any erroneous segregation of the laundry.

Another object is to provide a checking system of a sort in which sets of laundry carrying tags or checks are adapted to fit upon key racks whereby the operator in assorting the laundry can visionally and quickly observe the particular rack adapted to receive the tagged piece which he is about to segregate in the system, thereby eliminating loss of time in fumbling or attempting to fit the checks or tags to the wrong key rack.

Other objects reside in the particular construction and mounting of the key elements, cooperating with the respective group of tags, on the rack, these key elements being easily insertable in a standard or uniform rack to provide unlimited range of key combinations.

Further objects and advantages will be more fully set forth in the description of the accompanying drawings forming a part of this specification, in which:

Figure 1 is a side view of the rack showing it mounted upon a wall and illustrating a plurality of tags or checks hung thereon.

Figure 2 is a plan view of Figure 1 further illustrating the rack.

Figure 3 is a sectional view taken on line 3-3, Figure 2, detailing the key arrangement at the end of the rack.

Figure 4 is a face view of one of the laundry carrying tags or checks showing the cut-out portion therein for cooperation with the key rack.

Figure 5 is a side view of the tag or check shown in Figure 4, showing the laundry attaching pin depending from the tag.

Figure 6 is a view showing a series of the key racks mounted on a wall in systematic order.

The device concerned herein comprises a key bar or rack having key elements at the outer end thereof adapted to cooperate with laundry carrying tags or checks which are to be slid past the key elements onto the supporting portion of the rack. The key elements more specifically described are figures punched out of flat metal and facing the tag receiving end of the bar. The upper and lower portions of the figures extend above and below the outline of the flat rack bar in which they are mounted so as to either block introduction of the tags onto the bar or to cooperate with slots in the tags, when the tags are correctly applied, for permitting them to be slid and hung on the rack. The figures are arranged in different combinations for the respective racks, these combinations being arranged across the width of the bar or rack end and readable from the tag receiving end of the bar.

Referring to the drawings, the rack is indicated generally at 1. It is shown as supported or hung on a wall 2 by means of a slotted portion 3 of the rack engaging over a screw 4 extending from the wall 2. Only a single key rack or support member has been illustrated in detail, the general view (Figure 6) showing a plurality of these supported in a like manner along the wall in rows for systematic segregation of the laundry or other articles.

The racks are L-shaped, having a portion 5 thereof extending horizontally from the wall. A comparatively wide piece of bar metal is used in the construction of the rack so as to give the necessary width for the arrangement of the key elements 6 at the outer end of the horizontally extending portion of the rack. The outer end of the portion 5 has a rectangular opening 7 therein, the key elements being mounted along the rearwardly disposed margin of this opening 7.

Each key element comprises a figure indicated at 8 stamped from flat metal and secured to a mounting block 9 having a dovetailed portion at the rear secured by spreading the metal within a corresponding cut-out portion in the rearwardly disposed margin of the opening 7. The range of figure combinations is, of course, unlimited, since all that need be done to incorporate more figures in the key combination is to widen the bar. The laundry carrying checks 10 are also of flat metal, a set being provided for each rack.

The tags of a set are punched out at the upper end in precisely the outline of the rack and key elements or figures mounted thereon. That is to say there is a punched out portion 11 corresponding to the cross-sectional shape of the bar forming the rack and the cut-out portion in the upper and lower margin of the rectangular portion corresponding to the portions of the figures 8 extending 10 above and below the bar. Pins 12 of a standard type are inserted or hung from apertures 13 at the lower end of each tag, the pins being adapted to be attached to the various pieces of laundry comprised in that group. 15 The various numbers and their respective mounting blocks are easily assembled in the bar, inasmuch as they are held in place by slightly spreading the mounting so as to engage the groove in which they fit.

20 In using the rack the operator can distinguish which rack the particular laundry carrying tags he has in hand are adapted to be fixed upon, since the numbers making up the key elements are read from the rack end 25 at which he stands when he slides the tags on the rack. The use of numbers as a key system eliminates the loss of time in trying to insert the tag upon a rack to which it does not belong. As the various identifying 30 tags carrying their respective pieces of laundry are picked from the wash it is noted to which rack they belong and they are thus readily segregated by this system of assorting or grouping the laundry. Not only is 35 it made impossible to place the laundry upon the wrong rack but it is made easier to select the proper rack.

Having described my invention, I claim:

1. A system of the class described, comprising, a series of brackets and a set of check tags adapted to be inserted on each bracket, each bracket having a different arrangement of cut-out figures inserted at its tag receiving end, and each set of check tags having apertures therein configurated to correspond to the outline of the cut-out figures of its particular bracket for allowing only the tags of a certain set to be slid past its corresponding bracket figures and supported on the 50 bracket.

2. A system of the class described, comprising, a plurality of key racks and a set

of check tags for each key rack, each key rack having thereon a different combination of cut-out figures interposed in the path of entrance of the tags onto the rack, and each set of check tags having an aperture configurated to correspond to the outline of the particular cut-out figures of its respective bracket, and said tags having means attached thereto for supporting various articles to be segregated on the racks.

3. A checking device for the purpose described and for use in a system, comprising, a set of tags, a bar having an attachment portion and a tag supporting portion, a set of figures formed from flat stock and arranged across the width of the bar in the tag receiving end thereof, said figures arranged to be read from said receiving end, and said tags having cut-out portions corresponding to the outline of the figure combinations and the bar cross section so as to be slid past the figures onto the bar.

4. A checking device of the class described, comprising, a set of check tags, a rack bar having an attachment portion and a check supporting length, cut-out figures secured at the outer or check receiving end of said bar, said figures arranged to extend beyond the outline of the bar cross section so as to be in the path of entrance of the checks onto the bar, said set of check tags having apertures therein configurated to correspond to the cross section of the bar and the outline of the figures so as to be slid past the same.

5. A checking device of the class described, comprising, a set of check tags, a rack bar having an attachment portion and a check supporting length, said check supporting length having an aperture in its outer end, cut-out key figures formed from flat stock, mounting blocks for each figure, said mounting blocks dove-tailed into the margin of the aperture, said figures extending beyond the outline of the bar, and said check tags having apertures therein corresponding to the outline of the bar and figures, whereby they may be slid past the figures and supported upon the bar.

In witness whereof, I hereunto subscribe my name.

RUSSELL O. SCOTT.
